UNITED STATES PATENT OFFICE.

JOSEPH P. DEVINE, OF BUFFALO, NEW YORK.

VACUUM PUMP AND COMPRESSOR FOR MILKING MACHINES.

Application filed October 3, 1921, Serial No. 504,972. Renewed February 15, 1927.

This invention relates to vacuum pumps and compressors and one of the objects of the invention is to provide a machine adapted to operate a pulsating device such as is employed in milking machines wherein the use of valves or other parts of mechanism requiring the use of oil or water is eliminated.

Another object of the invention is to produce a new and improved machine of the above character, so constructed that it can be built in a series of stages, units or sections whereby the apparatus may be adapted for use to produce any desired degree of vacuum or pressure, thus eliminating the necessity of constructing different sized models and saving the incident expense of providing separate patterns for the production of different sized machines.

Another object of the invention is to provide a neat, compact and economically constructed vacuum pump and compressor and combining therewith a pulsating device wherein all danger of foreign substances contacting with the milk or entering the milk passages or conduits is eliminated.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings wherein I have illustrated a preferred form of embodiment of my invention;

Figure 1 is a view in elevation partially in section showing my improved machine,

Figure 2 is a plan view of the apparatus shown in Figure 1,

Figure 3 is a sectional view taken on line 3—3 of Figure 1, showing the pulsator when in position for what is known as the massaging operation,

Figure 4 is a similar sectional view showing the pulsator when in the position for drawing milk from the udder of a cow,

Figure 5 is a vertical sectional view upon an enlarged scale showing the pumping apparatus and the manner in which this part of the machine may be built up in sections,

Figure 6 is a horizontal sectional view taken on line 6—6 of Figure 5 through the

suction veins of the impeller and diffusion rings,

Figure 7 is a detail view in elevation of one of the impeller rings, and

Figure 8 is a similar view of one of the diffusion rings.

Similar reference characters refer to similar parts throughout the several views of the drawings.

Before proceeding with the description of the structural features of the machine comprising my invention, it may first be noted that one of the principal disadvantages or drawbacks in vacuum milking machines or systems has been the difficulty of preventing lubricating oil or other foreign substances coming in contact with the exhaust whereby the milk is contaminated or rendered unclean in its passage from the udder of the cow to the receptacle. In my improved machine I have eliminated these and other disadvantages by providing an apparatus wherein the use of lubricating oil or water seals is entirely eliminated, as will be evident from the description of the said machine set forth here below.

Referring now to the drawings, the reference numeral 1 indicates the base of the machine which is fitted to or forms the cover of the milk pail or container 2. Mounted upon the base 1 are the walled sections 3 forming the exterior casing of the pump, said sections being joined and fitted together at the points 4, all the sections being securely held together by the clamp bolts 5 which extend from the bottom of the casing to the top part or cap 6. This arrangement of parts forms a jacket or casing for what I term "diffusion rings" 7 and "impeller rings" 8, each section 3 having an inwardly extending portion or flange 9, which parts for purposes of this description may be referred to as intermediate diffusion rings. The sections 3 and the diffusion rings 7 are built up in stages or layers bearing or resting upon one another by means of the projections 10 and 11. The impeller rings 8 are built up in corresponding stages and each of said impeller rings 8 is provided with suction veins or passages 12 formed between the projections 10 or raised portions 13 and the walls 14. These suction veins 12, when the impeller rings 8 are rotated, make connection with veins or guideways 15 and 16 formed between the projections 10 and 11 of the diffu-

sion rings 7. The impeller rings 8 are secured to a shaft 19 by the keys 20 and are so disposed upon each other that clearance is provided for their rotation between the 5 diffusion rings 7 and 9, all the parts last described being concentrically positioned with reference to the shaft 19. The suction veins 12 of the impeller rings 8 and the veins or guideways 15 and 16 of the diffusion rings 10 7 are so disposed and related with reference to each other that air pumped or projected forward by the veins of one impeller is diffused or conducted by said veins or guideways 15 and 16 to the next or neighboring 15 impeller, it being understood that the more impellers and their associated diffusion rings the greater will be the vacuum produced and the higher will be the pressure.

An electric motor (not shown) but mounted 20 in the housing 22, supplies the motive power for the machine, said housing 22 being mounted upon a split casing 23 which houses the pulsating mechanism presently to be described. The bolts 6 securing this 25 upper structure in a single unit to the uppermost section 3 of the machine. The electric motor (not shown) but which is mounted in the housing 22 and for which may be substituted any desirable source of motive power, 30 drives by means of the shaft 24 (driven by the motor), pulley 25, belt 26, pulleys 27 and 28, belt 29 and pulley 30 mounted upon a reduced portion 31 of the shaft 19.

In the present instance the ratio of increased transmission is approximately 5 to 1. In the present instance it is desired to drive the impeller rings at a very high speed, that is to say, they are driven at a high enough speed to produce the desired vacuum 40 and build up the desired pressure without the use of valves or water seals. I contemplate driving the motor at a speed of several thousand revolutions per minute which would result in driving the shaft 19 and the 45 impeller rings carried thereby at a very high rate of speed, it having been determined that the desired results are best attained at a high rate of revolution.

The pulley 30 is secured by means of a 50 clamp nut 32 upon the tapered portion 33 of the reduced portion 31 of the shaft 19 and the impeller rings are held in place upon the shaft 19 by means of the clamp nut 34 and a collar 35 formed near the lower end of the 55 shaft 19. Bearings 36 and 37 composed of suitable bearing metal are provided for the shaft 19.

Referring now to the pulsating mechanism illustrated in Figures 1 and 2, this mechanism 60 comprises a plunger 40 provided with the valves or ports 41 and 42, said plunger being slidable within a chamber 43 provided in the upper part of the split casing 23. This plunger is pivoted at 44 to a strap 45 65 and its eccentric 46, the latter being secured

to a driving disc 47, carrying a sun pinion 48 keyed at 49 to the planetary or sun gear 50, the latter engaging a drive pinion 51 connected to the pulley 25 mounted upon the motor shaft 24. Actuated by the driving disc 47 the sun pinion 48 engages the stationary rack 52 which engagement compels said sun pinion 48 to revolve in a planetary movement around the central shaft 24, thereby producing a reciprocating movement of the plunger 40 through the driving transmission of the pinion 51 and the planetary gear 50. This disposition of parts provides for the proper or desired reciprocation of the plunger 40, the present arrangement providing for pulsations of about 45 per minute which number of pulsations is considered about right for the intermittent massaging and suction produced upon the teat of the cow.

Having thus described my invention, the operation thereof, which from the foregoing should be largely obvious, may now be understood.

In the use of my improved apparatus the base or cover 1 thereof is mounted upon the milk pail or container 2 indicated by the dotted lines in Figure 1, and suitable line connections are extended from the side walled portion of the chamber or cylinder 43 as indicated by the dotted lines in Figures 2, 3 and 4, further connections (not shown) being made to the teat cups upon the udder of the cow, it being unnecessary to show these parts inasmuch as the application of similar machines is well known in the art. The cover portion 1 may be provided with valves 55 and 56 which control the milk flow into the pail 2 from the hose connections 57 and 58 leading from teat cups (not shown).

When it is desired to start the milking operation the switch 59, controlling the leads to the motor, is turned on starting the motor 22 whereby the impeller rings are rotated at the high rate of speed hereinbefore described between the diffusion rings 7 and 9, the diverging veins 12 of the impellers withdrawing the air from the vacuum chamber through the port 60 and through the instrumentality of the diffusion rings gradually build up the pressure. It is to be noted that the projections or raised portions 13 have a sharp cutting edge at the points 38, thus providing for the greatest of efficiency in the operation of the impellers. The veins or guideways 15 and 16 are set at the desired angularity with respect to the veins of the impeller to diffuse or conduct the air from one impeller to its neighbor, the air being compressed at the point of the exhaust outlet 61.

I have found it desirable to maintain a pressure of about three (3) pounds at the exhaust outlet and a partial vacuum at the inlet port.

Referring now to Figures 3 and 4, the exhaust 61 and the vacuum inlet 60 have connections 63 and 64 respectively with the pulsating chamber or cylinder 43 which connections are adapted to communicate by means of the ports 41 and 42 of the plunger or piston 40 with the connections 65 and 66, the latter being connected with the teat cups. The plunger or piston in its reciprocating movement driven by the gear mechanism previously described, alternately connects and disconnects by means of the ports 41 and 42 the connections 63 and 64 with their corresponding connections or passageways 67 and 68. In Figure 4 of the drawings the port 42 is shown in communication with passageways 68 and 70, the latter port leading to the connection 64, whereby the ports are connected for the suction operation in the drawing of milk, the connection 64 providing the source of suction from the outlet 61 of the pump, the connection 66 leading to the inside of the teat cup (not shown).

In Figure 3 of the drawings the port 41 of the plunger is shown in communication with the passageways 67 and 68 for the compression of the air to apply the necessary pressure required in massaging the teat of the cow and to relieve the suction, the connection 63 communicating the pressure from the pump and the hose connection 65 to the interior chamber of the teat cup (not shown). Port 71 provides for the discharge of the air pressure when the vacuum is employed for drawing the milk.

It will accordingly be seen that I have provided a machine well adapted among others to attain all the ends and objects above pointed out in a very simple and facile manner. By arranging the impeller and diffusion rings in the manner above described and relating the impeller and diffusion veins as shown in the drawings I am able to produce the desired amount of vacuum and pressure without the employment of valves or seals requiring the use of lubricating oil and water, whereby the milking operation is rendered safer for the producer and the milk is kept in a cleaner and more wholesome condition for the consumer.

As many changes could be made in this construction without departing from the scope of the following claims, it is intended that all matter contained in the above de-

scription or shown in the accompanying drawings shall be interpreted as illustrative only and not in a limiting sense.

Having thus described my invention what I claim as new and desire to secure by Letters Patent is:

1. In apparatus of the character described, the combination with a milk container, of a rotary air pump having a vacuum chamber and a compression chamber, teat cup connections in communication with the container, a pulsating device mounted upon the pump, a driving shaft, means for connecting the driving shaft and said pulsating device to drive the device, means for connecting the said driving shaft and the said pump to operate the pump, and air-conducting connections whereby the said pulsating device is in communication with the vacuum chamber and the compression chamber of the pump.

2. In apparatus of the character described, the combination with a milk container, of a rotary air pump having a vacuum chamber and a compression chamber, teat cup connections in communication with the container, the said pump having a central vertical shaft, a pulsating device mounted upon the pump and having a driving shaft aligned with the said pump shaft, means for connecting the driving shaft and the pump shaft to operate the pump, and air-conducting connections whereby the said pulsating device is in communication with the vacuum chamber and the compression chamber of the pump.

3. In apparatus of the character described, a milk container having a removable cover, the said cover having teat cup connections, an air pump mounted upon the said cover and having a vacuum chamber and a compression chamber, a pulsating device mounted upon the said pump, a motor mounted upon the said pulsating device and having a downwardly extending driving shaft, means for connecting the driving shaft and the pulsating device to operate the device, means arranged between the said device and the pump for connecting the said driving shaft and pump to operate the pump, and air-conducting connections whereby said pulsating device is in communication with the vacuum chamber and the compression chamber of the pump.

In testimony whereof, I affix my signature.
JOSEPH P. DEVINE.
